UNITED STATES PATENT OFFICE.

EUGENE E. HENRY, OF ASTORIA, OREGON, ASSIGNOR OF ONE-HALF TO HOWARD S. GILNETT, OF ASTORIA, OREGON.

AUTOMATIC VENDING AND CHANGE-MAKING MACHINE.

1,084,011.

Specification of Letters Patent.

Patented Jan. 13, 1914.

Application filed March 6, 1913. Serial No. 752,333.

To all whom it may concern:

Be it known that I, EUGENE E. HENRY, a citizen of the United States, and a resident of Astoria, in the county of Clatsop and State of Oregon, have invented a new and Improved Automatic Vending and Change-Making Machine, of which the following is a full, clear, and exact description.

10 My improved machine, although capable of use for delivering various merchandise, is more particularly designed for embodiment in a ticket-vending and money-changing machine in which coins of different denominations may be inserted, and change delivered to the value of the inserted coin, or in which coins or equivalent checks of varying value may be inserted and tickets and change be delivered to the value of 20 the said coin or other check.

For the indicated purpose I make use of a series of holders to hold the coins and tickets, ejector slides associated with the holders, a series of actuating levers for the 25 slides, and a master lever adapted to receive a coin or other check in various positions to connect the master lever with a particular actuating lever according to the value of the check or coin, and I arrange the 30 several levers so that certain of them may move in unison according to the particular check inserted in the machine.

The distinguishing features of my invention, and the important structural elements 35 characterizing the preferred embodiment which is illustrated as an example, will be more particularly explained in the specific description hereinafter to be given.

Reference is to be had to the accompanying 40 drawings forming a part of this specification, in which similar characters of reference indicate corresponding parts in all the views.

Figure 1 is a perspective view of a machine embodying my invention; Fig. 2 is a plan view; Fig. 3 is a transverse vertical section; Fig. 4 is a view similar to Fig. 3, but omitting the levers, except the master lever; Fig. 5 is a detail vertical section of 50 one of the holders; Fig. 6 is a longitudinal vertical section; Fig. 7 is a sectional plan

view; and Fig. 8 is a fragmentary detail, given to show a modified form of the actuating levers.

In constructing the machine embodying 55 my invention in accordance with the illustrated example, a suitable case 10 is provided, and in bearings 11, 11^a therein is supported a rock shaft 12, surrounding which are hollow concentric shafts 13, 14, 15, the 60 rocking of which shafts serves to cause the delivery of change or merchandise from one or more of a series of stacks 16, 17, 18, 19, constituting holders for superposed series of coins or other articles 20, illustrated conventionally in the present instance as coins. The hollow shafts are respectively held in position by collars 21 having set screws 24.

Each rocker shaft has a rocker arm 12^a, 13^a, 14^a, 15^a, the respective arms being connected by links 28, 29, 30 and 31 with horizontal ejector slides 32, 33, 34, 35, arranged in the base 10^a of the stacks and formed with openings 36 adapted to receive the lowermost coin or coins in a stack. 75

Each rocker shaft has an actuating lever, the levers being preferably of different lengths; thus the shaft 12 has an actuating lever 38; the shaft 13 an actuating lever 39; the shaft 14 an actuating lever 40 and 80 the shaft 15 an actuating lever 41. A master lever 42 has its hub loosely sleeved on the hollow bearing 11^a, in which one end of the shaft 12 is supported and is provided with a handle 43 projecting outward through the 85 case 10, and adapted to move in a slot 10^b in the top of the case. The master lever has a slot 44 for receiving a coin 45, or equivalent check, there being a check slot 10^c in the top of the case transecting the slot 90 10^b to permit entrance of the coin to the slot 44 of the master lever when the latter is in the normal position.

The coin or check 45 is adapted to be intercepted by one of the actuating levers according to the value of the check. The means to intercept the coin may be seats on the respective actuating levers; thus the top of the lever 38 terminates in a curved seat 38^a; the lever 39 terminates in a curved seat 39^a; and 100 the lever 40 terminates in a curved seat 40^a. The bottom wall 44^a of the slot 44 constitutes

an additional seat to receive the smallest check. The several seats for the checks as illustrated, are arranged to receive coins, the seat 44^a being adapted to receive and intercept a dime; the seat 38^a to intercept a twenty-five cent piece; the seat 39^a to intercept a fifty-cent piece, and the seat 40^a to receive and intercept a silver dollar. The depositing of a dime in the slot 44 will result in the dime resting on the seat 44^a, and adjacent to said seat there is provided on the first lever 38^a, a member 38^b in such a position as to lie in front of the coin, the latter being indicated in dotted position at 45^a, so that the forward rocking of the master lever 42 will cause the coin 45^a to engage the member 38^b and carry forward the lever 38, to rock the shaft 12, and through the rocker arm 12^a and link 28, the ejector slide 32 will be moved. Similarly there is a member 39^b on the lever 39, adjacent to the seat 38^a of the lever 38, so that a coin 45^b intercepted by the lever 38 will engage the member 39^b and carry forward the lever 39. The lever 40 has a member 40^b adjacent to the seat 39^a of the lever 39 to be engaged by a coin 45^a, and the lever 41 has a member 41^b adjacent to the seat 40^a of the lever 40, to be engaged by a coin 45. The lever 38 is free to move forward alone, but in order to carry said lever forward by a movement of the adjacent lever 39, the lever 38 is formed with a trip 38^c lying in the path of movement of the lever 39. Similarly the lever 39 has a trip 39^c projecting in front of the next lever 40, and the lever 40 has a trip 40^c projecting in front of the lever 41.

It will be seen that in the described construction, the seats 38^a, etc., formed by the upper ends of the actuating levers, and the members 38^b, 39^b, etc., for engagement by the coins, constitute selective elements variously positioned with respect to the master lever 42, whereby coins of varying values will automatically select the lever or levers to be moved forward to actuate an ejector or combination of ejectors. Thus with the machine adapted to deliver change for coins from a dime to a silver dollar, the depositing of the dime will, upon the rocking of the master operating lever 42, cause the lever 38 only to move forward and only the shaft 12 will be rocked, which will cause the ejector slide 32 to be moved. Said slide is of a thickness to receive two nickels, as indicated in Fig. 6, so that the forward movement of the slide will eject two nickels as change for the deposited dime.

If a twenty-five cent piece be inserted, the two levers 38, 39, will be selected by the said coin for the forward movement in combination, the seat 38^a on the lever 38 serving to intercept the coin, and the member 39^b will be engaged by the coin as the master lever moves forward. The coin will thus serve

for direct connection between the master lever 42 and the lever 39, and by reason of the trip 38^c on the lever 38, both levers 38 and 39 will move forward, and through the arms 12^a, 13^a, and links 28, 29, both slides 32, 33 will be actuated. The slide 33 as seen in Fig. 6, is of a thickness to receive and eject three nickels, and as the slide 32 ejects two nickels, there will be delivered to the exterior tray 37, five nickels as change for the deposited twenty-five cent piece.

Upon the deposit of a fifty-cent piece 45^c, the levers 38, 39, 40, will be automatically selected by said coin, as the seat 39^a will intercept the coin in position to engage the member 40^b of the lever 40 to connect the latter lever with the master wheel. The forward movement of the lever 40 will carry forward the lever 39 by reason of the trip 39^c, and the lever 38 by reason of the trip 38^c, so that the three levers will move forward in combination, and will rock the shafts 12, 13, 14, and through the connections of the rocker arms and links, the slide 34 will be actuated in addition to the slides 32 and 33. The stack 18 with which the slide 34 is associated, is adapted to receive twenty-five cent pieces, and the hole 36 in said slide is of a thickness to receive one twenty-five cent piece, so that the latter piece with the five nickels discharged by the slides 32, 33, will total 50 as change for the deposited coin 45^c.

The stack 19 in the arrangement shown, is designed to contain fifty cent pieces, and upon the deposit of a silver dollar 45, the latter will be intercepted by the seat 40^a of the lever 40 and connect the master lever 42 with the lever 41, by reason of the member 41^b on the latter lever. By reason of the trips 40^c, 39^c, 38^c, four actuating levers will now be moved forward operating all ejector slides, and discharge to the delivering tray 37 one fifty cent piece, one twenty-five cent piece, three nickels and two nickels.

The master lever 42 with the deposited coin is adapted to move forward adjacent to a plate 46 as far as a channel or chute 47, which leads to a drawer 48 or its equivalent. Within casing 10 opposite the channel 47, is a guard 49, between which and the channel the master lever is adapted to move, said guard having fingers 50 separated by slots 50^a, the latter being adapted to accommodate the members 38^b, 39^b, etc., on the actuating levers.

The master lever has a normal range of movement from the position shown in Figs. 3 and 4 to the channel 47, at which point the coin is free to escape from the coin slot or passage 44 in the lever to the drawer 48. Adjacent to the path of movement of the master lever between the normal idle position thereof and the channel 47, a series of resilient catches 51 are provided, with either

one of which the coin in the slot 44 will contact so that after the coin is carried past a particular catch, the latter will spring outwardly behind the coin, and prevent return 5 of the lever to the original position, so that after the lever with a coin has been moved forward to carry a coin past a catch 51, the lever must be given a full forward movement to the channel 47, to permit escape of the 10 coin before the lever can be returned. The provision of the catches will thus prevent repeating. The catches 51 are formed preferably on the plate 46, and said plate has lateral members 46^a (Fig. 6), between which 15 are concave recesses 46^b, the said projections and recesses being adjacent to the idle position of the master lever, and the opposed side edge 42^b of the master lever is correspondingly formed; the arrangement is such 20 that coins of a predetermined denomination may pass the projecting members 46^a. The opposite side edge 42^c of the master lever 42 is approximately stepped to correspond with the decreasing size of the successive actuating 25 ing levers.

To return the various levers to the original position after a forward movement, a retractile spring 52 is provided, which has connection at one end with the case 10, and 30 at the opposite end with the master lever 42. In order that the return of the lever 42 will cause the return of any of the actuating levers that have been carried forward, a pin 38^k is provided on the actuating lever 38 and projects laterally in the rear of the master lever. Since in all cases the lever 38 will move forward with the master lever when any coin has been deposited, the return of the master lever will engage the lateral 40 pin 38^k and carry said lever 38 rearwardly. The return of the lever 38 will, by reason of the trips 38^c, 39^c, 40^c, carry with it any additional actuating levers (39, 40, 41) that have been moved forwardly.

45 The rearward or return movement of the master lever is limited by a stop screw 53, which takes into a transverse partition 54. Instead of directly contacting with the screw 53, the master lever has a plate spring 55 on 50 the back thereof, which brings up against the forward end of the screw 53. The strength of the plate spring 55 is such that it will not be overcome by the spring 52, and the contact of the spring 55 with the screw 53 will locate the master lever with its coin slot or passage 44 in register with the coin inlet 10^c of the case. I provide means, hereinafter described, to prevent any particular ejector slide being actuated in case 55 the coins or other articles to be delivered are exhausted in the particular stack associated with that slide, and in case an ejector slide has thus been prevented from moving forward after a coin has been deposited, the 60 master lever 42 may be given an abnormal

rearward movement by the operator grasping the handle 43 and pulling the lever rearwardly against the tension of the plate spring 55, until the coin slot 44 of the lever comes opposite a channel or chute 56 constituting an emergency coin-outlet, so that the coin will escape to a tray 57 and thus be recovered by the depositor. As one expedient for preventing movement of a slide upon the coins on a particular coin being exhausted, a gravity follower 58 may be employed, in each stack 16, 17, etc., the follower being in the form of a weight which may have, if desired as shown in Figs. 4 and 5, an eye 58^a for the attachment of a withdrawal cord or chain (not shown).

In connection with the change-making devices as described, I provide a combined change-making and ticket-delivering mechanism, the same in all respects as that just described, except for a modification in the stacks to hold both the tickets and coins, and a corresponding modification in the ejecting slides, there being three ejecting slides instead of four. A shaft 12^b is arranged coaxial with the shaft 12, and supported in the bearing 11 at one end, and at its opposite end is a sleeve bearing 11^b. Similarly, concentric shafts 13^b and 15^b are provided corresponding with the shafts 13, 15, the shafts having rocker arms 12^c, 13^c, 15^c connected by links 28^a, 29^a, 31^a, with ejector slides 32^a, 33^a, 35^a. The slide 32^a operates at the base of ticket stack 16^a; the slide 33^a is at the base of a duplex stack comprising 100 a coin stack 17^a and a ticket stack 17^b, and the slide 35^a operates at the base of a duplex stack comprising a coin stack 19^a and a ticket stack 19^b. Set collars 21^a, 22^a, secured by set screws 24^a hold the rocker shafts in 105 their respective positions. The rocker arms 12^c, etc., may be connected with their respective links 28^a, etc., by screw pins 27^a, and similar pins may connect the said links with the ejector slides 32^a, etc. The slide 32^a has 110 a rectangular opening 36^b to receive and discharge the lowermost ticket 20^b in the stack 16^a. The slide 33^a has a rectangular opening 36^b to receive a ticket, and also an opening 36^a to discharge a coin, which in the instance shown is designed to be a nickel. The slide 35^a has an opening 36^b adapted to receive and eject two tickets 20^b, and an opening 36^a adapted to receive and eject one nickel. 115

Three actuating levers 38^d, 39^d, 41^d are provided respectively on the shafts 12^b, 13^b, 15^b; the upper end 38^e of the lever 38 forms a seat for a coin; a second seat 38^f is formed on the lever below the first seat, and at a 125 still lower point there is formed on the master lever 42^d, a coin seat 42^c. The upper end 39^e of a lever 39 forms the fourth seat for a coin. The lever 38 has a member 38^g projecting toward the master lever above the 130

lowermost seat 42^a, to be engaged by a coin on said seat when the master lever moves forward, and a second member 38^b to be engaged by a coin, the arrangement being such that the lever 38 will be connected with the master lever either by a dime or by two nickels, as hereinafter explained.

In order that the lever 38^a may be actuated by a forward movement of the lever 39^a, said lever 38^a has a trip 38^b in the path of movement of the lever 39^a, and to a similar end the lever 39^a has a trip member 39^c in the path of movement of the lever 41^a. The lever 39^a also has a member 39^d adjacent to the coin seat 38^e, to be engaged by a coin connecting the said lever with the master lever, and for a similar purpose the lever 41^a has a member 41^e adjacent to the seat 39^e to be engaged by a coin.

With the described construction, and with tickets and nickels in the stacks as described, an inserted dime, indicated in dotted position at 45^a, will be intercepted by the seat 42^a at the lower end of the coin passage 44^a in the master lever 42^a, in a position to engage the trip 38^b on the lever 38^a, so that a forward movement of the master lever will rock the lever 38^a of the shaft 12^b and actuate the slide 32^a to eject one ten cent ticket. If two nickels be deposited in succession, the first will be intercepted by the seat 38^e on the lever 38^a, and the second nickel will rest on the first one in line with the trip 38^b on the lever 38^a, and connect the latter lever with the master lever so that the same result will follow the depositing of two nickels as if a dime had been deposited, and the ejector slide 32^a will deliver a ten cent ticket to the delivery tray 37^a. If a twenty five cent piece be inserted it will be intercepted by the seat 38^e on the lever 38^a, in a position to engage the trip member 39^c of the lever 39^a, and a forward movement of the master lever will then carry forward the lever 39^a and also the lever 38^a by reason of the trip member 38^b. The forward rocking of the levers 38^a and 39^a, in combination, will actuate the slides 32^a, 33^a, the former delivering one ten cent ticket and the latter delivering one ten cent ticket and one nickel change.

If a fifty cent piece be inserted, as indicated by the numeral 45^a, it will be intercepted by the seat 39^e of the lever 39^a, in line with the member 41^e on the lever 41^a, and a rocking of the master lever will now, it is obvious, rock all three actuating levers 38^a, 39^a, 41^a in combination and in unison, and all three slides 32^a, 33^a, 35^a will be actuated, the first delivering one ten cent ticket, the second slide delivering one ten cent ticket and one nickel, and the third slide delivering two ten cent tickets and one nickel. The same provision is made in connection with the combined vending and change-making

mechanism as previously described for the return of a coin to the owner if the ejector slides are prevented from moving forward by a dummy follower 58, and upon an abnormal rearward movement of the master lever 42^a, which is provided with a handle 43^a, the coin will be returned through the outlet channel or chute 56^a to a tray 57^a. The elements 47^a, 49^a, 50^a, 51^a, 52^a, 53^a, 54^a, 55^a, are the same in all respects as the corresponding elements in the described change-making mechanism.

In Fig. 5 there is represented in cross section a removable cover 60, which in practice may be locked by any suitable devices (not shown) in position over the stacks to prevent access thereto by unauthorized parties.

In Fig. 8 are shown actuating levers, each of which provides its own rest for the coin for actuating the lever, instead of the coin resting on an adjacent lever; thus two levers are shown, the one, 40^m, having a rest 40ⁿ thereon, so that the coin will be arrested by said ledge between the same and the inner surface of the plate 46, which plate, and the elements 46^a are, as previously described. Above the ledge 40ⁿ is the lateral projection 40^b, corresponding with the element 40^b. The lever 40 is provided further with a projection 40^b corresponding with the projection 40^c in Fig. 6. Similarly the lever 41^m corresponding with the lever 41, is provided with a ledge 41ⁿ as a coin rest, and with a member 41^b corresponding with the member 41^b in Fig. 6. Thus each lever serves to arrest the particular coin for operating that lever.

The described construction affords a practical means for carrying my invention into effect, and I would state in conclusion that I do not limit myself strictly to the mechanical details herein illustrated, since manifestly the same can be considerably varied without departing from the spirit of the invention.

Having thus described my invention, I claim as new, and desire to secure by Letters Patent:

1. In a check-controlled machine, the herein-described delivery mechanism comprising a series of holders for the articles to be delivered, a series of ejectors associated with the holders, a series of actuating levers operatively connected with the ejectors, certain of which levers are each provided with a trip to engage and move an adjacent lever upon a forward stroke, and a master operating lever adapted for connection with either of the actuating levers by a check connector, there being selective members on the actuating levers, variously positioned with respect to the master lever to intercept and engage a check connector.
2. In an automatic machine, delivery

mechanism comprising series of holders for the articles to be delivered, a series of ejectors to discharge articles from the holders, a series of individual actuating levers for the ejectors, certain of the levers having each a trip to engage an adjacent lever when advancing, a master operating lever, and means whereby to connect the master lever with either of the operating levers.

stacks, a series of concentric rock shafts operatively connected with the respective ejectors, a series of individual actuating levers for the rock shafts, certain of the said levers each having a trip to engage the adjacent lever when advancing and to be engaged by the said adjacent lever upon a return movement of the lever, a master lever, there being a passage along the master lever 70 to receive an insertible connector device to

10 3. In an automatic machine, delivery mechanism comprising a series of holders for the articles to be delivered, a series of ejectors to discharge the articles from the holders, a series of individual actuating levers for the ejectors, the said levers, except the first in the series, each having a trip to engage an adjacent lever when advancing, a master operating lever, there being a passage ranging lengthwise of the master lever for receiving a connector device to connect the master lever with either of the operating levers, and certain of the operating levers forming stops to intercept the connector device in position to engage an adjacent actuating lever, and each of the actuating levers having a member to be engaged by the connector device.

15 7. The combination with a series of holders for articles to be delivered, of a series of ejectors for the articles, a series of rock shafts operatively connected with the respective ejectors, a series of individual actuating levers for the shafts, the said levers, except the first, having trips to engage an adjacent lever in advancing and to be engaged by said adjacent lever upon a return movement of the latter, a master lever, there being a passage adjacent to the master lever to receive an insertible connector device to connect the master lever with a particular actuating lever, and there being members on said actuating levers along said passage to intercept a connector device and other members on adjacent levers to be engaged by the connector device.

20 85 25 90

30 4. In an automatic machine, a delivery mechanism comprising a series of holders for the articles to be delivered, a series of ejectors for the articles, a series of separate actuating levers for the ejectors, said levers, except the first, having each a trip to engage the adjacent lever in advancing and engageable by said adjacent lever upon return movement of the latter, and a master lever adapted to be engaged by an insertible connector device with either of the actuating levers, the several actuating levers having 35 members variously positioned with respect to the master lever, to be engaged by the connector device.

40 5. In an automatic machine, a delivery mechanism comprising a series of holders for the articles to be delivered, a series of ejectors for the articles, a series of separate actuating levers for the ejectors, said levers, except the first, having each a trip to engage the adjacent lever in advancing and engageable by said adjacent lever upon return movement of the latter, and a master lever adapted to be engaged by an insertible connector device with either of the actuating levers, the several actuating levers having 45 members variously positioned with respect to the master lever, to be engaged by the connector device.

95 6. In a machine for delivering articles, a delivery mechanism comprising a series of holders for articles to be delivered, a series of ejectors for ejecting the articles from the holders, a series of individual actuating devices for the ejectors, and a master operating device adapted to receive a connector check, there being selective members associated with the actuating devices for engaging the particular actuating device.

100 7. In a machine for delivering articles, a delivery mechanism comprising a series of holders for articles to be delivered, a series of ejectors for ejecting the articles from the holders, a series of individual actuating devices for the ejectors, and a master operating device adapted to receive a connector check, there being selective members associated with the actuating devices for engaging the particular actuating device.

45 5. In an automatic machine, a delivery mechanism comprising a series of holders for the articles to be delivered, a series of ejectors for the articles, a series of separate actuating levers for the ejectors, said levers, except the first, having each a trip to engage the adjacent lever in advancing and engageable by said adjacent lever upon return movement of the latter, a master lever adapted to be engaged by an insertible connector device with either of the actuating levers, the several actuating levers having 50 members variously positioned with respect to the master lever, to be engaged by the connector device, and certain of the actuating levers each forming a stop adjacent to the trip of an adjacent lever in advance 55 adapted to intercept the connector device and cause it to engage the connector with the said adjacent lever.

60

ing the check to connect a particular actuating device with the master operating device, and trips on the actuating devices for engagement with an adjacent actuating device when advancing, to move more or less of the actuating devices in unison according to the arrested position of the check connector.

65 9. In a check-controlled delivery mechanism, a holder for articles to be delivered, an ejector for the article, an actuating device for the ejector, and an operating lever adapted to receive a connector check in position to connect the operating lever with the actuating device, the operating lever having a normal range of movement to operate the actuating device, an outlet for permitting the escape of a connector check upon a forward movement of the operating lever, there being an escape outlet in the rear of the normal range of movement of the operating lever, said operating lever being ca-

11 12 13

6. The combination of a series of stacks to hold articles to be delivered, a series of ejectors for ejecting the articles from the 65 said adjacent lever, said operating lever being capable of an abnormal rearward movement to permit escape of the check through said 130

outlet, upon a failure of the operating lever to move forward to a position to release said check.

10. In a check-controlled delivery mechanism, a holder for articles to be delivered, an ejector for the articles, an actuating device for the ejector, an operating lever adapted to receive a connector check in position to connect said operating lever with the actuating device, the operating lever having a normal range of movement to operate the actuating device, an outlet for permitting the escape of a connector check upon a forward movement of the operating lever, and a catch adjacent to the said outlet along the path of movement of the connector device, to engage the latter and prevent its return with the operating lever, there being an escape outlet in the rear of the normal range of movement of the operating lever, said operating lever being capable of an abnormal rearward movement to permit escape of the check through said rear outlet upon a failure of the operating lever to move forward to the said catch.

11. In a delivery mechanism, a series of holders for the articles to be delivered, a series of ejectors for ejecting said articles from the holders, a series of individual actuating levers connected with the ejectors, certain of the levers each having a trip to engage an adjacent lever in advancing, and to be engaged by said adjacent lever upon a return movement of the latter, the said levers being provided with members to be engaged by a connector check, a master lever having a vertical passage therein to receive the connector device, an outlet for escape of the connector device upon a forward movement of the master lever, a guard at said outlet having fingers in staggered relation to the check-engaging members on the actuating levers, and a retractile spring for returning the several levers to the normal position.

12. In a delivery mechanism, a series of stacks for holding articles to be delivered, additional stacks for coins for the making of change, slides commanding the several stacks, a series of actuating devices for the

slides, a master operating device adapted to receive a check to connect the operating device with either one of the actuating devices, the actuating devices having stops to intercept a check in different positions to engage particular actuating devices, and means for operatively connecting a particular series of actuating devices to move in unison according to the position of the check, to operate a particular group of slides and discharge articles and change corresponding with the particular check.

13. In a check-controlled delivery mechanism, a holder for articles to be delivered, an ejector for the articles, an actuating means for the ejector, an operating lever adapted to receive a connector check in position to connect the said lever with the actuating means, the operating lever having a range of movement to cause the delivery of an article from the holder, an outlet permitting escape of the connector check from the operating lever, and a catch along the path of movement of the operating lever, to engage the connector check and prevent return movement of the lever until the check escape therefrom.

14. In a check-controlled delivery mechanism, a series of holders for articles to be delivered, a series of ejectors for the articles, actuating means for the ejectors, including individual actuating levers having a coin passage, a master lever, and members adjacent to the path of movement of the master lever permitting the passage only of predetermined checks, the actuating levers being of varying heights to present approximately a stepped arrangement, and certain of the levers serving at their upper ends as interceptors for a check, to locate the latter in position for engagement with adjacent levers.

In testimony whereof I have signed my name to this specification in the presence of two subscribing witnesses.

EUGENE E. HENRY.
